UNITED STATES PATENT OFFICE.

MORTIMER L. PACKER, OF COLUMBUS, OHIO.

DESIGN FOR A PORTABLE HEATER.

42,699.

Specification for Design.

Patented July 2, 1912.

Application filed March 16, 1912. Serial No. 684,337. Term of patent 7 years.

To all whom it may concern:

Be it known that I, MORTIMER L. PACKER, a citizen of the United States, residing at Columbus, in the county of Franklin and State of Ohio, have invented a new, original, and ornamental Design for Portable Heaters, of which the following is a specification, reference being had to the accompanying drawing, forming part thereof.

The figure shown is a view in perspective of a portable heater having my new design.

I claim:

The ornamental design for a portable heater, as shown.

MORTIMER L. PACKER.

Witnesses:

C. C. SHEPHERD,

A. L. PHELPS.
